(57)

CLAIM

The ornamental design for the arithmetic and control unit, as shown and described.

DESCRIPTION

FIG. 1 is a perspective view of front, top and right side of the arithmetic and control unit showing my new design; FIG. 2 is a perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The portions of the article shown in broken lines form no part of the claimed design.

1 Claim, 6 Drawing Sheets(56)
